UNITED STATES PATENT OFFICE.

WENZEL WOCASEK, OF BELLEHELEN, VIA TONAPAH, NEVADA.

GRIDDLE GREASER.

Application filed January 28, 1924. Serial No. 689,059.

This invention comprises a handle 1 provided with a ferrule or tubular extension 2 at one end thereof, this said extension being threaded interiorly as shown at 3. A rag 5 securing bell 4 is provided the same having an elongated tubular shank 8 which is rotatively anchored in the extension 2 in any conventional manner. A bit 5 is provided, having a threaded shank 6 adapted to be 10 inserted through the bell 4 and tubular shank 8 into the extension 2 where it is held by threaded engagement. By holding the bit 5 and bell 4 against rotation and rotating the handle 1, the threaded shank 6 is either projected outwardly through the tubular shank 15 or is drawn inwardly, depending upon the direction of rotation of the handle 1.

In use the bit 5 is first projected outwardly by turning the handle 1 as described; after 20 which one end of the rag 7 is caught upon the bit 5 and the entire rag is then wound upon the bit. The bit 5 and a portion of the attached rag are then drawn into the bell 4 by reversing the rotation of the handle 1; 25 whereby the rag is firmly locked into place. It is thus apparent that I have provided a device of the kind described embodying means for easily and quickly attaching or detaching the rag, as and for the purpose intended, and while I have herein described a certain specific method of constructing and 30 assembling the elements of my invention, it is understood that I may vary the same in minor details, not departing from the spirit 35 of my invention, as defined in the appended claims.

In the drawing—

Figure 1 is an elevation of the device with a rag attached;

Figure 2 is an elevation with the rag removed;

Figure 3 is an end view regarding the instrument from the bit end;

Figure 4 is a detail of the bit detached from the handle and showing the threaded shank;

Figure 5 is an end view of the handle showing the rag securing bell;

Figure 6 is a detail of the handle, a portion being broken out to show the threaded bore therein;

Figure 7 is a detail of a strip of rag as adapted to serve as a swab on this device.

I claim:

1. In a griddle greaser a device of the kind described, comprising a handle; an interiorly threaded ferrule at one end of the handle; a rag securing bell having an elongated tubular shank rotatively anchored in the said ferrule; and a bit adapted for engagement by a removable rag having a threaded shank adapted to pass through the said bell and tubular shank and threadedly engage the said threaded ferrule for securing said removable rag.

2. In a griddle greaser a device of the kind described, comprising a handle; a rag securing bell having an elongated tubular shank rotatively anchored to the handle, a bit adapted for engagement by a removable rag having a shank adapted to pass through the bell and into the tubular shank; and means for projecting the bit and its shank outwardly or drawing same inwardly, as desired for securing or removing said removable rag.

In testimony whereof I affix my signature.
WENZEL WOCASEK.
